UNITED STATES PATENT OFFICE.

ARTHUR R. MEEKS, OF COLUMBUS, GEORGIA.

TENSIONING DEVICE FOR SHUTTLES.

Application filed May 12, 1922. Serial No. 560,462.

To all whom it may concern:

Be it known that I, ARTHUR R. MEEKS, a citizen of the United States, residing at Columbus, in the county of Muscogee and State 5 of Georgia, have invented certain new and useful Improvements in Tensioning Devices for Shuttles; and I do hereby declare the following to be a full, clear, and exact description of the invention, such as will enable others skilled in the art to which it 10 pertains to make and use the same.

The present invention relates to improvements in tensioning devices for shuttles in which the filling strand is led through a 15 spring pressed device as it leaves the bobbin, and before it emerges through the eye of the shuttle whereby to avoid looseness in the filling which results in injury to the cloth, impairing its commercial value.

20 In the present operation of looms, the filling thread is found to slough off the spool in such wise as to create a tangled mass of the thread in the shuttle. This tangled mass is woven into the cloth, and causes unevenness, and often results in the breaking of 25 the thread.

An object of the invention is therefore to prevent rapid unwinding of the filling thread from the spool except as it is directly 30 required for proper weaving in the cloth, to accomplish this by a relatively small and compact device admitting of its placement in the shuttle without alteration in the construction thereof and without affecting the 35 movements of the spool or the proper progress of the filling thread.

Another object of the invention resides in providing a device for the above purposes which will be inexpensive to make, easy to 40 install, accessible at all times, and effective in its action of placing a check or restraint upon the undue unwinding of the filling thread.

With the foregoing and other objects in 45 view, the invention will be more fully described hereinafter, and will be more particularly pointed out in the claims appended hereto.

In the drawings, wherein like symbols refer to like or corresponding parts throughout the several views,

Fig. 1 shows a fragmentary plan view of a shuttle with the improved device mounted therein;

55 Fig. 2 is a longitudinal section of the same;

Fig. 3 is a side view of the improved tensioning device on an enlarged scale;

Fig. 4 is a front view of the same; and

Fig. 5 is a cross section of the device 60 through the tension arms.

Referring more particularly to the drawings, 1 designates a shuttle, a portion of which is illustrated in Figs. 1 and 2; and 2 represents a bobbin or spool fitting in the 65 shuttle in the customary manner, and having wound thereon the filling strand 3.

After passing through the head of the shuttle the filling strand 3, as indicated in Fig. 1, emerges through the shuttle eye 4, 70 it being drawn out from the spool as the shuttle moves back and forth in the race. The improved tensioning device is situated within the shuttle adjacent the delivery end of the spool 2, and in a position to directly 75 receive the filling strand 3.

The improved device consists of a pair of arms 5 and 6 preferably of metal, and of a slightly resilient character. The arms are provided with upper free extremities 7 and 80 8 bent in opposite directions to form flaring jaws for guiding the filling strand down between the arms 5 and 6. If desired the sides of the shuttle may be cut away, as indicated at 9, to receive the upper portions 85 of the jaws 7 and 8 whereby to act as guides in the opening and closing of the jaws and associated arms. Below, the arms are supported by diagonal bases 10 and 11 converging upwardly from the lateral portions 12 90 and 13, which are joined by a connecting bar 14. The device is provided further with a shank 15, illustrated in Figs. 2, 3 and 4, the same being elevated above the plane of the connecting bar 14, a web 16 joining these 95 parts together. An opening 17 is made in the shank 15 to receive an appropriate fastening by which the device is secured in the shuttle head.

A coil spring 18 is fitted between the lateral portions 12 and 13 of the yoke, which portions are situated suitably far apart to receive a spring of the requisite number of turns. A bolt 19 passes axially through the spring 18 and through the lateral parts, 105 while a nut 20 threaded upon the opposite end of the bolt engages adjustably against the outside face of the other lateral yoke part.

In the use of the device, the same is mounted in the shuttle as appears in Figs. 1 and 110 2; whereupon the filling 3 is drawn into con-

tact with the flaring jaws 7 and 8 and guided between the arms 5 and 6. Now the arms and yoke of which they form a part are of resilient metal and the bending of the metal 5 is such as to cause the arms to spring yielding together upon the filling and impose the required tension. In this action the arms are resisted by the coil spring 18 tending to open the arms. The nut and bolt adjustment 10 restricts the scope of action of the spring. Thus there are two forces acting in opposite directions upon the arms 5 and 6 which makes them extremely sensitive. This sensitivity may be accurately gauged and finely 15 adjusted by the nut 20. The device therefore provides an adjustable tension which is regulated in accordance with the character of the filling and will avoid the sloughing off of the latter and its massing in the head 20 of the shuttle.

The shank 15 lies within the shuttle head and is appropriately secured therein, while the web 16 strikes against the head and acts to steady the device and to prevent lateral 25 creeping or casual movement further into the head. The jaws 7 and 8 are also guided in the cut-out portions 9 of the shuttle and the light spring arms are therefore unmoved by the passing of the filling except, of 30 course, the normal opening and closing movement thereof.

I have illustrated and described a preferred and satisfactory embodiment of my invention, but it is obvious that changes

may be made therein within the spirit and 35 scope thereof as defined in the appended claims.

What is claimed is:

1. A tensioning device for shuttles comprising a metallic yoke having substantially 40 parallel arms brought together upon the filling and having free extremities, the portion of the yoke adjoining the arms being relatively wide, resilient means placed in the relatively wide portion of the yoke, and adjusting means also connected with the relatively wide portion of the yoke, substantially 45 as described.

2. A tensioning device for shuttles comprising a yoke made from a single piece of 50 sheet metal having a relatively broad connecting portion bent to provide lateral parts remote from each other and a pair of filling engaging arms relatively close together and having unconnected free ends, spring means 55 mounted between the relatively wide parts of the yoke member and a tensioning bolt passing through the spring and connecting the relatively wide parts, and a shank also formed in the same piece from the yoke and 60 extending at substantially right angles to the arms and being off-set slightly from the plane of the connecting portion of the yoke, said shank adapted to receive fastenings for connecting the device to a shuttle, substantially 65 as described.

ARTHUR R. MEEKS.
